M. N. JONES.

COFFIN,

APPLICATION FILED NOV. 7, 1916.

1,224,383.

Patented May 1, 1917.

INVENTOR.
MARSHALL N. JONES.

W. W. Boughton
ATTORNEY.

UNITED STATES PATENT OFFICE.

MARSHALL N. JONES, OF DENVER, COLORADO, ASSIGNOR TO NATIONAL GLASS CASKET COMPANY, A CORPORATION OF COLORADO.

COFFIN.

1,224,383.

Specification of Letters Patent.

Patented May 1, 1917.

Application filed November 7, 1916. Serial No. 129,946.

To all whom it may concern:

Be it known that I, MARSHALL N. JONES, a citizen of the United States, and a resident of Denyer, in the county of Denver and State of Colorado, have invented a certain new and useful Improvement in Coffins, of which the following is a full, clear, and exact description.

My invention is an improvement in coffins or burial caskets and its principal object is the provision of a coffin made of glass and strengthened by metallic reinforcing members embedded in a portion of the same so that it will still retain its shape even if the glass of which it is made become cracked or broken. Another object of my invention is to provide independent supporting or carrying means extending around the coffin, thus relieving the structure of strains and leverage to which it would be subjected if the supporting handles were secured merely to its sides or if the load has to be carried by the structure itself. A still further object of my invention is the provision of a coffin with ornamental supporting or carrying means which are adapted to be readily and quickly removed if it is desired that the coffin should not carry the same when lowered into the grave. Further and more particular objects and advantages of my invention will later appear in this specification.

In the single sheet of drawings accompanying this application and forming a part hereof—

Figure 1 is a perspective view of a coffin made according to my invention;

Fig. 2 is a longitudinal, vertical section through the center line of Fig. 1;

Fig. 3 is a bottom plan view of the coffin shown in Fig. 1, a portion of the wooden skids with which the bottom is provided being broken away;

Fig. 4 is a partial transverse vertical section through the coffin shown in Fig. 1;

Fig. 5 is an end view of the same; and

Fig. 6 is an end view of a slightly modified form of my invention.

According to my invention, the coffin is made of molded glass and is in two parts, the base B and the cover or lid C. While it will be obvious that, if desired, reinforcing elements may be employed throughout the device, in the preferred embodiment of the same shown in drawings these reinforcements are comprised only in the base B.

They are embedded in the glass during the operation of molding, being inserted in the mold prior to the pouring or pressing of the glass. While in the mold, the reinforcing wires 10 (see Fig. 4) are suspended in position by the metallic strap member 11, the wires 10 being provided at their upper ends with loops which pass around the strap member 11 from inside to outside. In addition to the circumferential reinforcing elements 10, I prefer to add horizontal reinforcing elements 12, which may or may not be tied to the elements 10, as preferred. Just above the strap member 11 the mold is shaped to give the base B a shoulder 13 and, after the molding operation is complete, there is secured to the strap member 11 below this shoulder a finishing band 14, which is attached to the strap member 11 by screws or the like 15. This band 14 serves the double purpose of concealing the exposed ends of the reinforcing elements 10 and of forming a means for attachment of the carrying means and the cover or lid hinges.

In order that the casket may be adapted to slide, it is necessary that its base be furnished with skids. I therefore core out slight recesses in the base, rectangular in shape, which extend almost to the ends of the base, as clearly shown in Figs. 2 and 3. Fitting within these recesses, but projecting therebelow on account of their greater thickness, there are inserted wooden skids 16, which are provided with a plurality of transverse openings. These skids are held in place by several ornamental appearing wires 17, which pass through small openings 18 in the skids and are secured between the strap member 11 and the band 14. No strain is exerted on these wires, they being merely for the purpose of preventing the skids from dropping out of their recesses when the coffin is lifted.

As previously stated, the strain exerted by the load, constituted by the weight of the casket and its contained body, is not carried by the casket structure itself but by a supplemental structure. In the preferred form of the invention, shown in the first five figures, this supplemental structure consists of a plurality of casket engaging and supporting bands 19, which may be formed of heavy silvered wire or the like and which pass around the casket and are provided at their ends with loops 20, which engage the 110

supporting rods 21. In the preferred form, illustrated in said first five figures, these bands are not integral but are divided at their middle point, where they are provided 5 with loops, these loops each engaging a longitudinally extending rod 22. The rods 21, which also serve to constitute handles for carrying, are slidably mounted in arms 23, which are in turn pivoted in sockets carried 10 by the band 14. Links 24, located at either end of the base, are preferably provided for retaining the rods 21 in position either swung down close to the casket body, as shown in the drawings, or in extended position 15 to conveniently serve as handles. Slots 25, provided with slightly enlarged ends, as shown, are provided in the links 24 for this purpose. The loops 20 are so proportioned that when the rods or handles 21 20 are in extended position the loops 20 engage the rods 21 and serve to take the load. Threaded knobs 26 on the ends of the rods 21 serve to retain the rods 21 and the links 24 in proper relation and, when unscrewed, 25 permit the ready separation of the supporting means.

The upper surface of the rim of the base B is provided with a recess 27 adapted to receive a similarly shaped projection 28 on 30 the cover; when it is desired to seal the casket this recess is filled with any suitable cement and when the cover is lowered and the cement had an opportunity to set the casket will be hermetically sealed.

35 The cover or lid C is provided with a band 29 suitably secured thereto and embraced behind a shoulder 30. To this band at the rear are secured the hinges 31, these hinges being also attached to the band 14 40 on the base B. A handle 32 for conveniently manipulating the lid or cover C is also secured to the band 29.

In the operation of molding the base B I prefer to form within the interior thereof 45 and adjacent the upper edge suitable lugs 33 on which a wire 34 may be supported for the purpose of attaching thereto the customary trimming or lining of the coffin.

It will be obvious that, if desired, for the 50 divided bands 19 there may be substituted integral bands 35, as shown in Fig. 6, which bands are provided with loops at their ends and which extend from one rod 21 to the other. In this instance it is only necessary 55 to make the openings in the skids 16 large enough so that the loops 20 may readily pass therethrough.

If bodies are interred without suitable 60 embalming, the gases formed by decomposition will serve to rupture any hermetically sealed coffin and for this reason I prefer to provide a relief valve 36, which is indicated in Fig. 2. This valve is preferably spring pressed and opens in an outwardly

direction only, being normally seated to prevent the entrance of moisture or the like. 65

One principal advantage of a casket such as I have described in this application is its low cost of manufacture. This is particularly true when the cost of the ornamental 70 trimmings is not considered. Therefore if the greater portion of these trimmings can be removed before the casket is lowered into the grave, the expense incurred can be materially lessened. With my construction if 75 it is desired to remove these trimmings this may be conveniently and quickly done by withdrawing the rod 22, removing a pair of knobs 26, and withdrawing the rods 21. The bands 19 are thereby freed and may at 80 once be collected. This releases the major portion and almost all of the expensive trimmings for use in another instance.

A further advantage of a coffin made as is the present one, of non-perishing material, 85 is that when sealed it also serves the purpose of a vault.

Having thus described my invention, 90 what I claim and desire to secure by Letters Patent is:

1. A coffin comprising a base and a cover, said base being composed of a glass structure having embedded therein a metallic reinforcing structure comprising a horizontally circumferential strap member the outer face of which is exposed, a finishing band secured to said circumferential strap member, a longitudinally extending rod at each side of said base and supported by said finishing band, and a plurality of supporting bands extending under said base and connected at their opposite ends to said rods. 95

2. A coffin comprising a base and a cover, 100 said base being composed of a glass structure having embedded therein a metallic reinforcing structure comprising a horizontally circumferential strap member the outer face of which is exposed, a finishing band secured to said circumferential strap member, a longitudinally extending rod at each side of said base and pivotally connected to said finishing band, and a plurality of supporting bands extending under said base and connected at their opposite ends to said rods by elongated loops. 110

3. A coffin comprising a base and a cover, 115 said base being composed of a glass structure having a finishing band therearound, longitudinally extending rods at each side of said base and pivotally connected to said finishing band, a plurality of centrally divided supporting bands extending under said base and connected at their opposite ends to said rods by elongated loops, and removable means for connecting the sections of said supporting bands at the point of division. 120 125

4. A coffin comprising a base and a cover, said base being composed of a glass structure having a finishing band therearound, a longitudinally extending rod at each side of said base and connected by pivoted arms to said finishing band, a plurality of supporting bands extending under said base and connected at their opposite ends to said rods by elongated loops, and a slotted link 10 adapted to retain said rods in extended or retracted position.
5. A coffin comprising a base and a cover, said base having a finishing band therearound, a plurality of arms pivoted to said band at each side of said base, a longitudinally extending rod slidably mounted in 15 said arms at each side of said base, thread-
- ed knobs retaining said rods in position, and a plurality of supporting bands extending under said base and connected at their opposite ends to said rods by slotted links. 20
6. A coffin comprising a base and a cover, said base having recesses in its bottom and a circumferential strap member embedded in its body adjacent its upper edges, skids 25 fitting in said recesses, wires passing through said skids and having their ends adjacent said strap member, and a finishing band secured to said strap member and clamping the ends of said wires thereto. 30

In testimony whereof I hereunto affix my signature.

MARSHALL N. JONES.
